US0D1043887S

(12) **United States Design Patent** (10) **Patent No.:** **US D1,043,887 S**
(45) **Date of Patent:** **** Sep. 24, 2024**

(54) **PART OF MODULAR PUMP TRACK**

(71) Applicant: **PARKITECT s.r.o**, Valasska Polanka (CZ)

(72) Inventor: **Erik Dzintars Burgon**, Jablunka nad Bevou (CZ)

(73) Assignee: **PARKITECT S.R.O**, Valasska Polanka (CZ)

(**) Term: **15 Years**

(21) Appl. No.: **29/862,702**

(22) Filed: **Dec. 12, 2022**

Related U.S. Application Data

(62) Division of application No. 35/512,149, filed on Jun. 18, 2021 (U.S. filing date under 35 U.S.C. 384), and having an international filing date of Jun. 18, 2021, now Pat. No. Des. 976,355.
